DEVICES FOR HANDLING ELONGATED ARTICLES
Alfred Schmermund, 62 Körnerstrasse, Gevelsberg, Westphalia, Germany
Filed June 1, 1965, Ser. No. 460,336
Claims priority, application Germany, June 11, 1964, Sch 35,306
8 Claims. (Cl. 221—1)

The invention relates to devices for handling elongated articles, for example cigarettes, cigarillos or cigars, and more specifically to devices for supplying batches of predetermined numbers of such articles for magazines to feed members.

In machines for packing cigarettes, the cigarettes to be packed are placed into hoppers from which they drop into counting chutes arranged therebeneath, cigarettes being delivered in batches of predetermined numbers of cigarettes from the free ends of the chutes to containers which are transferred to conveyor tables on to which the cigarettes are discharged in batches from the containers for being fed along the conveyor tables to packing stations at which the batches of cigarettes are subjected to a desired treatment. Usually in each packing machine, a plurality of containers are provided and arranged so that at least one container is charged with cigarettes and at least one other container is discharged, the discharged cigarettes being fed on to a conveyor table. Such arrangements have been disclosed in my United Kingdom patent specification No. 881,068.

While the arrangements of said patent specification have worked satisfactorily it is an object of my present invention still further to improve the previous arrangements.

In such arrangements the time needed for filling cigarettes into the containers is longer than the time needed for discharging the containers. Therefore, a limitation is imposed on the operating speed of the previous arrangements by the time needed for filling the containers. It is another object of my present invention to remove such limitation and to obtain a higher operating speed, other conditions being equal, than is obtainable by the previous arrangements.

These and other objects and advantages of the invention will become apparent to those skilled in the art when reading the following detailed description of a specific embodiment of my invention which is given by way of example and which is somewhat diagrammatically illustrated in the accompanying drawings, in which:

FIG. 1 illustrates an arrangement of the invention in elevation;

FIG. 2 illustrates a plan view taken along the line II—II of FIG. 1;

FIG. 3 illustrates a side view, partly in section;

FIG. 4 illustrates various operating steps; and

FIG. 5 illustrates linkages between various parts of the arrangement.

The arrangement illustrated comprises two conveyor paths I and II for feeding elongated articles to a packing or other treatment station. A magazine is provided which has a hopper 1 for loose cigarettes (which term is intended to embrace also cigarillos, cigars and other elongated articles), the hopper 1 having a funnel-shaped portion 25. In the hopper roof—like separating members 16 are provided for guiding cigarettes into groups of chutes 2, smaller roof—like elements 15 being provided for relieving pressure exerted by the cigarettes from the chutes 2 which, in use, are arranged so that cigarettes can pass through the chutes 2 under the action of gravity.

2

Four groups of chutes 2 are provided, the groups being indicated by LL; LR; RL; and RR. Beneath the chutes 2, a bottom plate 24 is provided. Between the lower ends of the chutes 2 and the bottom plate 24, slides 9 and 10 are reciprocatably provided and arranged to move in opposite senses. Each of the slides 9 and 10 is U-shaped at one end, the U-shaped ends 7a and 7b of slide 9 and the U-shaped ends 8a and 8b of the slide 10 being slotted to form discharging fingers corresponding to the distances of the respective chutes 2 from one another, the slotted ends 7a, 7b, 8a and 8b extending into the range of the chutes 2 and corresponding with regard to their width and height to cigarette batches to be supplied from the chutes 2. A pair of containers 3 is carried on a reciprocatable rod 42, and another pair of containers 3' is carried on another reciprocatable rod 41. The bottom of each container 3 and 3' has a slot 23 through which neck portions of push members 11 can pass, said push members 11 being fixed by cross bars 21 to conveyors 22 forming endless feed members, each conveyor 22 passing around guide wheels 13 mounted on shafts 14. Furthermore, guides 17, 18 and 20 are provided along which batches of cigarettes can travel when pushed by the push members 11 to a station for further treatment such as packing.

The slides 9, 10 and the reciprocatable rods 41, 42 are operable in timed relationship relatively to each other. This may be effected in any convenient and known manner as diagrammatically illustrated in FIG. 5, in which a drive 101 is linked through a cam and follower arrangement 102 to the slides 9, 10 and through a cam and follower arrangement 103 to rods 41, 42, the linkage being effected by means of lever arrangements 104 and 105. The arrangement illustrated operates as follows:

35 The slides 9 and 10 by means of their slotted ends 7a, 7b and 8a, 8b respectively, move alternately a batch of cigarettes from the respective group of chutes into containers 3, 3' which, at this instant, are opposite the lower open end of chutes 2. The conveyors 22 with the push members 11 move at a substantial constant speed and cigarettes are supplied from the hopper to the chutes 2.

40 FIG. 4 illustrates five operating positions a, b, c, d, a', of which the position a corresponds to the position illustrated in FIGS. 1, 2 and 3, positions a, b, c and d indicating four phases of an operating cycle, and the position a' corresponding to position a. Adjacent phases are displaced relatively to one another through 90°.

45 In the position a (and in the corresponding position a'), the containers 3 carried by the reciprocatable rod 42 are located in front of the chutes 2 of the groups LL and RL and are supplied with cigarettes from the respective chutes 2 by means of the slide 9. The containers 3' carried by the reciprocatable rod 41 are in alignment with the conveyor paths I and II and are emptied by means of the push members 11. The emptying of the containers 3' is effected within a short time while the arrangement is in position a. Contrary thereto, the feeding of cigarettes into the containers 3 takes a considerable time which is longer than the time during which the arrangement is in the position a. As will become clear from what follows, the feed of cigarettes to the containers 3 started already before the arrangement reached the position a. The reciprocatable rod 41 carrying the container 3' is now shifted as indicated by the arrow, whereby the arrangement assumes the subsequent position b. In position b, the containers 3 carried by rod 42 are still located in front of the chutes 2 of the groups LL and RL so that the feeding of cigarettes into the containers 3 can continue without interruption, whereas the containers 3' have been

shifted by the rod 41 to lie in front of the chutes 2 of the groups LR and RR so that the feeding of cigarettes into the containers 3' by means of the slide 10 can begin while the feeding of cigarettes into the containers 3 continues to completion.

The reciprocatable rod 42 carrying the containers 3 is now shifted as indicated by the arrow, whereby the arrangement assumes the subsequent position *c*. In the position *c*, the containers 3 carried by the rod 42 are in alignment with the conveyer paths I and II, and are emptied by the push members 11 while the feeding of cigarettes into the containers 3' continues. The reciprocatable rod 42 carrying the containers 3 is now shifted as indicated by the arrow, whereby the arrangement assumes the subsequent position *d*. In the positions *d*, the containers 3 carried by the rod 42 are in front of the chutes 2 of the groups LL and RL for feeding cigarettes into the containers 3, and the containers 3' continue to be fed with cigarettes from the chutes 2 of groups LR and RR. The reciprocatable rod 41 carrying the containers 3' is shifted as indicated by the arrow, whereby the arrangement assumes the subsequent position *a'* which is identical with the position *a*. In the position *a'*, the feeding of cigarettes into the containers 3 is continued and the containers 3' are discharged onto the conveyer paths I and II.

With the arrangement of my United Kingdom specification No. 881,068 herein before referred to all the containers for cigarettes were jointly displaceable so that each container was for half a cycle of operation in a position for being charged with cigarettes and for a subsequent half a cycle in a position for being discharged. Contrary thereto, in the arrangement just described, each container is in a position for being charged during $\frac{3}{4}$ of a cycle of operation and is in a position for being discharged only during $\frac{1}{4}$ of a cycle. The short time available for discharging is sufficient, and the longer time for charging each container can be fully utilized. Thus it is not necessary for a container to wait idling after it has been discharged until another container has been charged. By increasing the time available for charging and reducing the time during which a container remains in the discharge position; the total time required by a full cycle of operation can be kept short.

Modifications of the embodiment described and illustrated are possible. For example, the reciprocatable rods 41 and 42 carrying the containers may be replaced by other operating elements such as chains, segments, discs. Again, depending on requirements of each case, the operating cycle need not be subdivided into for equal periods, but may be subdivided in any other suitable manner. Again, instead of providing two conveyer paths, only one such path or more than two paths may be provided.

It should be clearly understood that further modifications, omissions and additions are possible without departing from the spirit of the invention.

I claim:

1. A device for handling elongated articles, comprising a magazine for said articles, said magazine having at least two groups of magazine openings, at least a first container and a second container for movement of said articles, at least one feed path means for said articles, first means for aligning said first container alternately with one of said groups of magazine openings and with said feed path means, second means for aligning said second container alternately with the other group of magazine openings and with said feed path means, said first aligning means being separate from said second aligning means, means for feeding articles to each container from the magazine through the said magazine openings when said container is aligned with one of said groups of magazine openings, means for discharging articles from each container when aligned with said feed path means and for moving the articles along said feed path means, and means for timing the operation of said first aligning

means, the said second aligning means, the feed means and the discharge means.

2. A device as defined in claim 1, wherein each container after having been discharged by said discharging means is aligned by one of said aligning means with one of said groups of magazine openings while the respective other container is still aligned with the respective other group of magazine openings.

3. A device as defined in claim 1, wherein said first aligning means comprise a first reciprocatable rod carrying said first container, and said second aligning means comprise a second reciprocatable rod carrying said second container, said timing means being arranged for reciprocating said rods in timed relationship relative to each other.

4. A device for handling elongated articles, comprising a magazine for said articles, said magazine having four groups of magazine openings, a first pair of containers and a second pair of containers for said articles, two feed paths means for said articles, first means for aligning said first pair of containers alternately with two of said four groups of magazine openings and with said two feed paths means, second means for aligning said second pair of containers alternately with the other two groups of magazine openings and with said two feed paths means, said first aligning means being separate from said second aligning means, means for feeding articles to each pair of containers when aligned with two of said four groups of magazine openings, means for discharging articles from each pair of containers when aligned with said two feed paths means and for moving the articles along the said feed path means, and means for timing the operation of said first aligning means, the said second aligning means, the feed means and the discharge means.

5. A device as defined in claim 4, wherein said first aligning means comprise a first support carrying said first pair of containers, and said second aligning means comprise a second support carrying said second pair of containers.

6. A device as defined in claim 5, wherein said first support comprises a first reciprocatable rod, and said second support comprises a second reciprocatable rod, said timing means being arranged for reciprocating said rods in timed relationship relative to each other.

7. A method of handling elongating articles comprising the steps of placing a first container in a first charging position, placing a second container in a discharging position, charging articles into said first container while discharging articles from said second container, placing said second container in a second charging position, charging articles into said second container while the charging of articles into said first container is being continued to completion, placing said first container in said discharging position, discharging articles from said first container while the charging of articles into said second container is continued, placing said first container in said first charging position, charging articles into said first container while charging articles into said second container is continued to completion, placing said second container in said discharging position, discharging articles from said second container while the charging of articles into said first container is being continued, and continuing the sequence of steps.

8. A method of handling elongated articles comprising the steps of placing a first pair of containers in a first pair of charging positions, placing a second pair of containers in a pair of discharging positions, charging articles into said first pair of containers while discharging articles from said second pair of containers, placing said second pair of containers in a second pair of charging positions, charging articles into said second pair of containers while the charging of articles into said first pair of containers is continued to completion, placing said first

pair of containers in said pair of discharging positions, discharging articles from said first pair of containers while the charging of articles into said second pair of containers is continued, placing said first pair of containers in said first pair of charging positions, charging articles into said first pair of containers while the charging of articles in said second pair of containers is completed, placing said second pair of containers in said pair of discharging positions, discharging articles from said second pair of containers while the charging of articles into said first pair of containers continues, and continuing the sequence of steps.
